UNITED STATES PATENT OFFICE.

CHARLES U. CARPENTER, OF NEW YORK, N. Y.

DESIGN FOR A HANDLE FOR DOCUMENT-FILES.

42,991.

Specification for Design.

Patented Sept. 10, 1912.

Application filed April 26, 1911. Serial No. 623,535. Term of patent 14 years.

To all whom it may concern:

Be it known that I, CHARLES U. CARPENTER, a citizen of the United States, and a resident of New York, in the county of New York and State of New York, have invented a new, original, and ornamental Design for Handles for Document-Files, of which the following is a specification, reference being had to the accompanying drawings, forming a part thereof.

Figure 1 is a front elevation of a handle embodying my invention; and Fig. 2 is a side elevation of Fig. 1.

I claim—

The ornamental design for a handle for document files, as shown.

C. U. CARPENTER.

Witnesses:

T. B. CARPENTER,
A. H. WRIGHT.
